UNITED STATES PATENT OFFICE.

EMIL HAEFELY, OF BASEL, SWITZERLAND, ASSIGNOR TO WESTINGHOUSE ELECTRIC AND MANUFACTURING COMPANY, A CORPORATION OF PENNSYLVANIA.

ELECTRICAL TRANSFORMER.

1,130,269.

Specification of Letters Patent.

Patented Mar. 2, 1915.

Application filed January 10, 1912. Serial No. 670,532.

To all whom it may concern:

Be it known that I, EMIL HAEFELY, a citizen of the Republic of Switzerland, and a resident of Basel, Switzerland, have invented 5 a new and useful Improvement in Electrical Transformers, of which the following is a specification.

It has heretofore been usual in transformers to insulate the high tension and low tension windings from each other and from the iron core by means of cylindrical sleeves composed of tough paper or cardboard, either alone or in combination with mica, or composed of mica only, these sleeves being disposed around the core, and between the high and low tension windings. As 10 both windings are usually of circular form, it has been usual to make the sleeves likewise of circular form, all the component parts of 15 the transformer being thus coaxially arranged. The unavoidable losses in the windings and in the magnetizable iron are converted into heat which is conducted away from the points at which it is produced by 20 means of a cooling medium consisting, in the case of comparatively low voltages, either of air or of oil, and in the case of high voltages, exclusively of oil. The windings and other parts of an oil-cooled transformer are 25 inclosed by a casing filled with oil, the heat generated at various points being transmitted to the oil, with the result that the portions of the oil which are first influenced by heat expand, becoming lighter and consequently rising, while the colder and 30 consequently denser portions of the oil press downward. In the upper end of the casing there is usually provided a cooling device consisting of a serpentine pipe through which cold 35 water is passed, so that the entire operation is constantly repeated, that is to say, there is a continuous circulation of the oil as long as the transformer is loaded and generates heat.

40 Insulating sleeves of the usual kind, as a matter of course, tend to take up heat from the oil which surrounds them; but they also generate on their own account a certain amount of heat due to dielectric hysteresis, 45 such heat being greater, the higher the potential difference in the transformer and the thicker the walls of the sleeves. From the preceding remarks it will be clear that it would be a considerable advantage if the oil

were caused to flow over and to cool both 55 the internal and the external surfaces of the insulating sleeves, as it is at these places that the greater part of the heat is generated. As it is necessary that the transformer should be as compact as possible one 60 winding is usually placed close to the insulating sleeve and only a small clearance is left on the other side between the sleeve and the other winding. Under such circumstances it may easily happen that the oil 65 gets locked in this clearance, that is to say, that on account of the great frictional resistance it cannot ascend, no matter how hot it may become, with the result that the insulating sleeve, becoming overheated, swells and 70 becomes soft, thus giving rise to the risk of rupture and short-circuiting from the high-tension to the low-tension winding of the core. It may moreover occur that small 75 quantities of water find their way from the cooling serpentine pipe into the oil, through leakage or sweating. This water traveling in the oil-circuit finds its way into the clearance above mentioned, where it may give 80 rise to the rupture of the insulating sleeve. 80

Now the present invention relates to an insulating sleeve of polygonal cross-section, that is especially suitable for oil transformers exposed to high electromotive forces, and that enables the cooling medium to be circulated 85 along both the inner and the outer side of the sleeve, while, moreover, it affords mechanical support to the windings; the arrangement being such that the places at which the sleeve comes in contact with the 90 inner and outer windings between which it is interposed in a transformer, do not lie exactly opposite to one another, but are displaced in relation to each other to the extent of half the length of a side of the sleeve. 95 For the said purpose of supporting the windings of the transformer, the sleeve itself is rigid and remains so forever, and forms a homogeneous hollow body closed in itself; it consists of paper or any equivalent 100 textile fabric which is wound in a continuous length under high pressure on a prismatic mandrel corresponding to the desired form of cross section of the sleeve, till the necessary thickness of the sleeve is obtained. 105

The accompanying drawing shows in cross section three examples of apparatus made in accordance with my invention. In

each of the forms of the apparatus shown in the drawing, an insulating sleeve 1 of polygonal cross-section or prismatic form is interposed between coils 2 and 3 of curved 5 or circular cross-section.

In Figure 1, the insulating sleeve is of octagonal cross section, while those shown in Figs. 2 and 3. have respectively decagonal and dodecagonal cross sections.

- 10 The places at which the inner and outer coils come in contact with each of the sleeves shown are displaced in relation to each other to the extent of half the length of a side of the sleeve, the arrangement being such that 15 the inner winding is in contact with the sleeve in the middle of each side, while the outer winding bears against the angles of the sleeve; there consequently occurs at each angle on the interior and at each side on the 20 exterior a spandrel that gives sufficient play for the circulation of the oil and for the cooling of the sleeve and of the windings separated thereby. With a sleeve of given dimensions, the less the number of its sides 25 and angles, the greater is the cross section of the spandrel-like spaces. It is a great advantage to have the sleeve support the two windings, *i. e.*, the high-tension and the low-tension windings, between which it is 30 interposed, as it thereby imparts to them the mechanical rigidity and support without which they might easily suffer damage in the case of considerable variations of load, short-circuits, and the like.
- 35 Having now particularly described and ascertained the nature of my said invention and in what manner the same is to be performed, I declare that what I claim is:—

1. Electrical apparatus comprising a coil 40 of curved cross-section and an adjacent insulating member of polygonal cross section, said coil engaging the insulating member at its vertices.

2. Electrical apparatus comprising a coil 45 of curved cross section, and a concentrically disposed insulating member of polygonal cross-section, whereby ventilating spaces are provided between adjacent surfaces of the coil and insulating member.

50 3. Electrical apparatus comprising a plurality of concentric circular coils and an insulating sleeve of polygonal cross-section interposed between and supporting the coils,

the outer coil engaging the insulating sleeve at its vertices. 55

4. Electrical apparatus comprising a plurality of concentric circular coils and an insulating sleeve of polygonal cross section interposed between the coils, the inner coil 60 engaging the insulating sleeve at points intermediate its vertices.

5. Electrical apparatus comprising a plurality of coils arranged one within the other, and an insulating sleeve of polygonal cross section interposed between and supporting 65 the coils, the circumscribed coil engaging the insulating sleeve at its vertices and the inscribed coil engaging the sleeve at points intermediate its vertices.

6. Electrical apparatus comprising a plurality of coils arranged one within the other, and an insulating sleeve interposed between and supporting the coils, the said coils and sleeve being relatively curved and polygonal in cross-section to provide spandrels between the sides of the sleeve and the circumscribed coil and between the vertices of the sleeve and the inscribed coil. 70

7. Electrical apparatus comprising a plurality of curved cross sectional coils arranged one within the other, and an insulating sleeve of polygonal cross-sectional form, and interposed between and supporting, the coils, whereby ventilating spaces are provided between adjacent coil and sleeve 85 surfaces, the ventilating spaces on opposite sides of said sleeve being displaced in relation to one another.

8. Electrical apparatus comprising a plurality of curved cross-sectional coils arranged one within the other, and an insulating sleeve of polygonal cross-sectional form interposed between the coils, whereby ventilating spaces are provided between adjacent coil and sleeve surfaces, the ventilating spaces on opposite sides of said sleeve being displaced in relation to one another to the extent of substantially half the length of one side of the polygon. 90

In testimony whereof I have signed my name to this specification in the presence of two subscribing witnesses.

EMIL HAEFELY.
